UNITED STATES PATENT OFFICE.

HENRY H. VAUGHAN, OF MONTREAL, QUEBEC, CANADA.

PASSENGER-CAR FRAME.

1,245,071.

Specification of Letters Patent. Patented Oct. 30, 1917.

Application filed September 10, 1913, Serial No. 789,168. Renewed June 13, 1916. Serial No. 103,581.

To all whom it may concern:

Be it known that I, HENRY H. VAUGHAN, of the city of Montreal, Province of Quebec, Dominion of Canada, a citizen of the 5 United States of America, have invented certain new and useful Improvements in Passenger-Car Frames; and I do hereby declare that the following is a full, clear, and exact description thereof.

10 My invention relates particularly to the features of passenger car bodies which contribute thereto self sustaining properties, and it has for its object to increase these properties and at the same time stiffen the 15 roof, the improvement being obtained without impairing the deck-sash openings.

To this end the invention may be said to consist of arched carlines of trefoil-arch form relatively braced by short purlins, 20 and these carlines and purlins supporting the deck-sash frames between them; a further feature consisting of the particular construction of roof frame to include short purlins, the latter acting as individual sills 25 for the deck-sashes for supporting the same in the external depressions of the trefoil.

For full comprehension, however, of my invention, reference must be had to the accompanying drawings forming a part of 30 this specification, in which similar reference characters indicate the same parts, and wherein;

Figure 1 is a diagrammatical transverse sectional view of a passenger car constructed according to my invention, one half being 35 illustrated with the wood work filled in, the other half showing the skeleton frame alone; and

Fig. 2 is a similar longitudinal view of 40 the deck portion of the car.

As the invention relates solely to the deck carlines and purlin and side sill structure, the remainder of the car body will receive only incidental mention and is shown for 45 the purpose, only, of illustrating the application of the different features of the invention.

My improved deck structure is clearly seen in Figs. 1 and 2; the carlines thereof

consist of trefoiled arch construction, each 50 comprising a pair of side arcs *b b* and a middle arc *c* rolled, pressed or otherwise formed from a single commercial angle bar. These carlines are supported by the side plates *h* and spaced in pairs, the pairs being 55 in turn spaced the proper distance apart to accommodate deck-sashes *d* by a series of joined short purlins *e* each extending from the center of one deck-sash to the center of the next, and secured to the carlines by 60 angle brackets *f* and supported by sub-carlines *g*. The main and sub-carlines are fastened in place bearing upon the side plates *h* by bent ends *h* of the flanges of both 65 forms of carlines, the upper ends of the sub-carlines having their flanges bent and riveted as at *i* to the purlins *e*.

The crowns of the deck-sashes are braced from the ridge pole *m* by bars *s*.

What I claim is as follows:

1. In a steel car monitor-roof, the combination with the sides of the car body, of carlines of trefoil arch form formed independently of said sides and having their lower ends supported thereon, a roof supported by said carlines and having deck-sash openings at the reentrant angles of the trefoil and conforming to the carlines in the cross-section of the car between said 75 openings and arched longitudinally of the 80 car over said openings, deck-sash frames supported in said openings, the longitudinal middle of the roof being supported at a height above the top of the deck-sash frames.

2. In a passenger car, the combination with spaced arched carlines, of purlins secured to the carlines each of such purlins extending from midway one of the spaces between the carlines to midway the adjoining space, and sub-carlines supporting and connecting the ends of one purlin with the 85 ends of the adjoining purlins.

3. In a passenger car, the combination with a roof having deck-sash openings, of spaced carlines of trefoil arch form the roof 90 conforming to the carlines between the deck-sash openings, purlins secured to the carlines each of such purlins extending from

midway one of the spaces between the carline to midway the adjoining space and in close proximity to the lower side edge of each adjacent deck-sash openings and sub-carlines supporting and connecting the ends of one purlin with the ends of the adjoining purlins.

In testimony whereof I have signed my name to this specification in the presence of two witnesses.

HENRY H. VAUGHAN.

Witnesses:

GORDON G. COOKE,

WILLIAM J. C. HEWETSON.
